UNITED STATES PATENT OFFICE.

FRED RICHARD WEATHERSBY, OF HOUSTON, TEXAS.

DRILL.

1,206,488.

Specification of Letters Patent. Patented Nov. 28, 1916.

Application filed August 30, 1913. Serial No. 787,458.

To all whom it may concern:

Be it known that I, FRED R. WEATHERSBY, a citizen of the United States, and a resident of Houston, in the county of Harris and State of Texas, have made certain new and useful Improvements in Drills, of which the following is a specification.

My invention relates to drills, and more particularly to drills of the kind employed for earth boring, my more particular purpose being to provide a comparatively simple drill, made preferably in a single piece, and having provision for accomplishing a number of distinct purposes.

More particularly stated I seek to provide a drill which may be mounted upon drill pipes of different diameters, and which carries a cutting blade so formed as to guide the drill accurately even when the drill encounters surfaces of varying degrees of hardness, and especially under conditions where drills of ordinary form would most likely be diverted from their proper paths of travel in descending into the earth.

Reference is made to the accompanying drawing forming part of this specification and in which like letters indicate like parts.

Figure 1 is a front elevation of my improved drill, Fig. 2 is a side elevation of the same, and Fig. 3 is a plan view of the drill.

A massive stem 4 having approximately a cylindrical form is provided with a thread 5 upon the surface of the stem where the stem is of large diameter, as will be understood from Fig. 1. The stem is provided with a substantially cylindrical portion 6 of smaller diameter, this portion having a thread 7. The stem is further provided with holes 8 extending through it in the general longitudinal direction of its longest axis, which is also its axis of rotation, while in action. A blade 10 is integral with the stem 4 and is provided with two cutting edges 11, 12, these edges terminating in points 13, 14 and meeting at a point 15. That is to say the edges 11, 12 meet to form a crotch at the point 15, as may be understood from Fig. 1. The lower ends of the holes 8, 9 are shown at 9^a and are upon opposite sides of the blade 10.

The drill may be cast, forged, pressed, or otherwise formed into shape, and may be made of any suitable material, though I preferably employ steel for the purpose.

The stem of the drill, as will be under-

stood from the foregoing description, has two portions—one of small diameter and the other of large diameter, these two portions respectively being provided with 60 threads and adapted to fit into the ends of hollow or tubular stems of the kind employed for supporting and turning drills of this general character.

In practical earth boring, as carried on 65 in some parts of the West, it is customary to employ drill pipes of either four inches internal diameter or six inches internal diameter, such pipes being provided internally at their lower ends with threads for 70 facilitating the fitting of the drill to be carried.

My improved drill above described is adapted to be mounted upon a pipe of small diameter—say four inches internal diameter, 75 by fitting the thread 7 into such pipe, or to be fitted upon a six inch pipe by use of the thread 5.

The stem is further provided with a shoulder 16 which serves as a limiting stop for 80 preventing the drill stem from extending too far into the pipe and serves also as an abutment for receiving the pressure of the pipe when fitted upon the portion 6 of smaller diameter of the stem. 85

The operation of my device is as follows: The operator determines whether he will use the drill in connection with a small pipe or with a large pipe. If the small pipe is to be used the portion of small diameter of this 90 stem is inserted into the pipe and secured thereto by aid of the thread 7. If the pipe of larger diameter is employed the thread 5 is used as above stated. Water is supplied through the holes 8, 9, in a manner well understood in this art. The pipe being located the drill is caused to turn and the cutting edges 11, 12 are brought to play upon the earth and rock to be drilled. Suppose now that the drill, in descending into the earth, 100 encounters a round hard substance such as a stone; suppose further that the stone is not located centrally beneath the drill, but is a little to one side of the center of the axial line thereof. In this event the points 13, 14 105 pass successively into engagement with the stone, first cutting a shallow groove of arcuate form and then gradually removing successive portions of the rock. The first of the points 13, 14 to engage the rock, by scoring 110 the rock makes a guide-way in which the other point can readily follow, so that there

is little or no tendency for the drill to be pushed sidewise or in any other manner displaced, by the pressure of the stone.

With drills of ordinary construction, as soon as one of the cutting edges or corners of the drill encounters a stone or rock, and especially if the latter be hard, smooth, and somewhat rounded, there is a great tendency for the drill, by its reaction upon the stone or rock, to be forced to one side and displaced relatively to its axis of rotation. My drill avoids this, because owing to the inclination of the edges 11, 12, the points 13, 14 serve in a sense as anchorages for preventing the drill from being displaced. In other words, the drill has approximately as much tendency to be drawn outwardly toward the rock as it has to be forced inwardly by the rock.

I do not limit myself to the precise construction shown as variations may be made therefrom without departing from the spirit of my invention.

By having two connections for different sized pipes, if the drill pipe happens to twist

off, one of the threaded portions 5 or 7 will enable another drill pipe to be secured to the drill in order to lift it out of the drill hole.

I claim:

The herein described drill comprising a substantially cylindrical stem, and a flat blade integral with the stem, the lower portion of the stem extending below the upper edge of the blade and being tapered downwardly and rounded, said blade being provided with oppositely facing cutting edges, inclining downwardly from the central portion to the ends of the blade, said stem being provided with a pair of bores arranged in a plane lying in acute angular relation with the blade and opening at points in the rounded and tapered portion of the stem above and intermediate the ends of the cutting edges and below the upper edge of the blade.

FRED RICHARD WEATHERSBY.
